US0D1017072S

(12) **United States Design Patent** (10) **Patent No.:** **US D1,017,072 S**
(45) **Date of Patent:** **** Mar. 5, 2024**

(54) **RETAIL KIOSK**

- (71) Applicant: **Apple Inc.**, Cupertino, CA (US)
(72) Inventors: **Kully Kraig Mandon**, Santa Cruz, CA (US); **Julien Phillip Stockwell**, San Francisco, CA (US)
(73) Assignee: **Apple Inc.**, Cupertino, CA (US)
(**) Term: **15 Years**
(21) Appl. No.: **29/842,398**
(22) Filed: **Jun. 13, 2022**

Related U.S. Application Data

- (63) Continuation of application No. 29/746,948, filed on Aug. 18, 2020, now Pat. No. Des. 955,602.

(57) **CLAIM**

The ornamental design for a retail kiosk, as shown and described.

DESCRIPTION

FIG. 1 is a top perspective view of a retail kiosk showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the retail kiosk that form no part of the claimed design.

The dot-dash broken lines in the figures show boundaries that form no part of the claimed design.

1 Claim, 6 Drawing Sheets
